CONTAINER ADAPTER FOR SPRAY GUNS

Filed May 2, 1938

UNITED STATES PATENT OFFICE

2,279,927

CONTAINER ADAPTER FOR SPRAY GUNS

Carl F. Noth, Chicago, Ill.

Application May 2, 1938, Serial No. 205,496

9 Claims. (Cl. 221—1)

This invention relates to a structure for converting a paint can into a spray cup for a spray gun. More particularly, this invention has to do with providing an adapter which will make a leak-proof fit with a paint can without damaging the lips of the paint can orifice.

During the past year or two, paint manufacturers have made available to paint users a special can having a protruding, pouring orifice. This type of can has made it possible to dispense with the spray cup attached to a spray gun by the simple expedient of attaching the can directly to the gun in the place of the spray cup. This elimination of the spray cup eliminates unavoidable wastage of paint. Under the new practise, the paint can, when a job is completed, is disconnected from the spray gun, its cover is replaced and it is returned to the shelf, there to remain until another job requires that particular paint. The only wastage of paint is that small amount left in the spray gun itself and in the adapter.

Existing adapters are unsatisfactory in that they do not obtain a proper purchase on the rim of the orifice of the paint can with the result that the comparatively weak material of the can is twisted and torn and the can wobbles in the adapter with resulting leakage of paint. If the adapter is applied to a can orifice a multitude of times, it is not long before the can orifice is so out of shape that it no longer affords a purchase to the gripping means of the adapter with the result that the paint must be removed from the can and the can thrown away. The principal object of this invention is therefore to provide a clamping means for the adapter having jaws of such shape and action as will obtain great purchase on the lip or rim of the orifice of a conventional paint can.

A second object of this invention is to render adjustable the distance between the adapter lid and the intake of the spray gun without the use of nuts and threads. In almost all spray guns the operating trigger is located so closely behind the intake tube that interference with the adapter will result unless the adapted can be adjusted to clear the trigger. In existing adapters, this variation is obtained by threaded tubes and nuts, and adjustment requires the expenditure of considerable time. Additionally, different threads are used on the intake tube of various makes of spray guns. It is desirable that the tube be easily removable from the adapter in order that a nut having the particular thread for the spray gun to be used may be slipped on the tube.

A third object of this invention is to provide a locking means having no hinge actions. Existing adapters lock the adapter lid to the paint can by means which become jammed by hardened paint. The invention, which is disclosed below, presents a locking jaw which can be withdrawn from the locking assembly for the purpose of cleaning.

The above and other desirable objects will appear hereinafter in the description of the invention with reference to the accompanying drawing comprising one sheet hereby made a part of this specification, and wherein:

Fig. 1 is a perspective view of the container adapter in unlocked position on top of a paint can;

Fig. 2 is a cross section of the device in locked position with a perspective view of a portion of a spray gun;

Fig. 3 is a fragmentary view of the locking means in unlocked position taken from the underside of the adapter and of a fragment of the adapter lid;

Fig. 4 is a view of the locking device taken on the line 4—4 of Fig. 3;

Fig. 5 is a fragmentary view of the fixed jaw of the locking means taken from the under side of the adapter and of a fragment of the adapter lid; and

Fig. 6 is a perspective view of the locking lever.

The same reference character is used in the specification that follows to identify a part as is used to indicate the same part in the drawings.

Examining my invention in detail, a conventional paint can is indicated by the numeral 10. This can 10 is termed conventional because in the last year or two it has become standard for paint to be applied through spray guns. Unlike the cans heretofore in general use, and still in use for most household paints, there is no inside annular channel around the edge of the top of can 10 which prevents the complete emptying of a can. Can 10 has a broad pouring orifice defined by the circular wall 11 which terminates in rolled lip 12. Attention is called to this rolled lip 12 which on its under side provides very little purchase for a gripping means, particularly where the gripping means operates at right angles to the arc of the lip. It is the failure to recognize the very limited purchase surface available on the underside of this lip together with the comparatively pliable nature of the can metal which is responsible for

the unsatisfactory results obtained from existing adapters. It should be borne in mind that the problem overcome by this invention results from the type of rim furnished on these cans and from the pliability of the metal used in the cans. Were the cans made of case hardened steel, there probably would be no need for this invention.

The base portion of the invention comprises a lid 13 stamped from sheet metal. The outside edge of this lid 13 is turned downward to form flange 14 which is continuous excepting for two check segments 15 and 16 turned outwardly and at right angles to the flange 14. These two check segments 15 and 16 are oppositely disposed and each check segment has a width of not less than ten degrees of the arc of the container orifice—that is measured along circular wall 11. Preferably these check segments have a width of about fifteen degrees of arc similarly measured. Raised in the under side of lid 13 is annular channel 17 which receives gasket 18.

Centrally of lid 13 wherein a hole has been cut is sunk cup 19 which is welded or soldered at its circumferential edge to lid 13. The method of creating this cup 19 is not deemed important and for production purposes, it is believed that this cup will be stamped directly from the lid 13. The cup 19 is perforated centrally to pass tube 20 hereinafter described.

The locking means or assembly which is generally identified by the numeral 21 comprises a piece of elastic strap material 22 having an elongated hole 23 in its central portion to pass tube 20. One end of strap material 22 is bent to form jaw 24 which is adapted to slip under check segment 15 and under the lip 12. The engaging edge of jaw 24 is curved in the same arc as the surface of circular wall 11. See Fig. 5. The other end 25 of strap material 22 is curved downward and slightly inward, leaving, however, sufficient clearance for slipping the end 25 over the lip 12 when the adapter is mounted on the can. In the end 25 is cut-out portion 26, rectangular in shape, and adapted to receive locking lever 27. The lower edge 28 of cut-out portion 26 is sharpened to engage groove 29 in the outer wall of locking lever 27. Locking lever 27 is stamped from a single piece of metal and is comprised of handle 30, inwardly curved portion 31 and broadened jaw 32, the engaging portion of which is a sharp edge curved in an arc approximating that of circular wall 11.

In its unlocked position, it should be noted that the locking means 21 permits the removal of the lid 13 from the can 10 because the distance between the inside edges of jaws 24 and 32 in released position exceeds the outside diameter of the orifice of can 10. On the other hand, the locking means 21 does not become disengaged from the lid 13 because of the check segments 15 and 16.

In assembling the container adapter, the medium soft, thick-rubber gasket 34 is seated in the cup 19. The locking lever 27 is slipped into the cut-out portion 26 by inserting the broadened jaw 32 side-wise through the cut-out portion 26 and then turning to its normal position. The locking means as a unit is then slipped from the side onto the lid, a metal washer 35 being inserted between the strap material 22 and the thick rubber gasket 34. This slipping of the locking means onto the lid from the side is indicated in Figs. 3 and 5 by the arrows 36 and 37. The strap material can be pressed outwardly suf-

ficiently so that point 38 will clear point 39 and point 40 will clear point 41. Once in position, the tube 20 is inserted from the top through elongated hole 23, washer 35, thick rubber gasket 34 and cup 19. The hole in the rubber gasket 34 is smaller than the diameter of tube 20 so that the tube is pressed through it with difficulty.

Describing briefly the remaining structure shown in Fig. 2, the tip 42 of tube 20 is hemispheric in shape and carries collar 43 against which presses nut 44 when the latter is screwed onto threaded intake 45 of spray gun 46. That portion of tube 20 lying within the can 10 is curved as at 47 so that the paint may be sucked from the side of the container when tilted. Attention is called to the trigger 48 of the spray gun 46. This trigger varies in length and position in the various makes of spray guns and one of the principal aims of this invention is to enable the spray gun user to adjust the paint can as closely as possible to the spray gun without interfering with the trigger.

When the locking means 21 is in unlocked position, the elongated hole 23 is slightly to the left of the position shown in Fig. 2 as is the entire locking means 21. As the locking lever is pressed down, the strap material 22 moves toward the locking lever 27, thus engaging jaw 24 with the underside of lip 12. When the locking lever 27 reaches the point where the groove 29 engages the edge 28, the adapter is locked to the can 10. To release, the strap material is pressed against the lid and the locking lever is readily disengaged.

As can be seen in the drawings, the two jaws 24 and 32 obtain a broad purchase upon the under side of lip 12 and jaw 32 actually is inserted, when in locked position, between the rolled portion of the lip 12 and the circular wall 11. The broad purchase obtained by these two jaws eliminates shearing and tearing of the lip and accomplishes the principal object of this invention.

When the locking means 21 is in unlocked position, the operator may make a quick adjustment of the tube 20 in relationship to the lid 13 and then lock the assembly. By so doing, the strap material bears tightly against the rubber gasket 34 which tightens around tube 20 and prevents tube 20 moving at right angles to the lid 13. Thus, without the use of nuts or threaded parts, a quick adjustment of the tube position has been effected and then the tube has been tightly positioned by the very locking means 21 which has fastened the adapter to the can 10. If it is necessary to use a lock nut having a different thread than lock nut 44, for example, the tube 20, when the adapter is in unlocked position, is withdrawn from the adapter, the nut required substituted, and the tube re-inserted into the adapter. This change is quickly effected when my adapter is used.

The operation of the strap material 22 against the rubber gasket 34 has the secondary effect of exerting an even pressure through the lid 13 upon the gasket 18 so that there is a tight, leak-proof fit between the lid and the can orifice.

The ease of assembling the various units or parts of the adapter indicates the ease with which they may be dis-assembled for cleaning purposes, a matter of considerable import where one is working in paint.

While I have shown and described only one embodiment of my invention, it is to be understood that the basic conception may be attained

by other structures without departing from the spirit of the invention, and therefore it is intended that the invention shall be in no wise limited excepting as defined in the appended claims.

I claim:

1. A container lid having a tube therethrough, compressible material between the tube and the lid, and means for compressing said compressible material simultaneously with the locking of said lid to a container.

2. A container lid having a cup therein, compressible material in said cup, a tube through said compressible material and said cup, and means for compressing said compressible material simultaneously with the locking of said lid to a container.

3. In combination with the outer lip of the orifice of a container and with a lid having a tube therethrough with compressible material between said tube and said lid, a locking means comprising a strap member having oppositely disposed jaws adapted to engage the under side of said lip, said strap member riding said tube and adjacent to said compressible material, and clamping means at the end of said strap member for clamping the strap material to the lip of the orifice whereby upon locking, the lid is tightened against the orifice through the compressible material and the lid is tightened to the tube by the compression of said member.

4. In combination with the outer lip of the orifice of a container and with a lid having a tube therethrough with compressible material between said tube and said lid, a locking means comprising a strap member having oppositely disposed jaws adapted to engage the under side of said lip, each of said jaws having a width of not less than ten degrees of arc of the orifice of the container, said strap member riding said tube and adjacent to said compressible material, and clamping means at the end of said strap member for clamping the strap member to the lip of the orifice whereby upon locking, the lid is tightened against the orifice through the compressible material and the lid is tightened to the tube by the compression of said member.

5. The same combination set forth in claim 4 with the additional factor that the locking means comprises a lever riding in a slot in one end of the strap member, said lever having a jaw adapted to engage the underside of the outer lip and having a slot to catch a sharpened edge of the slot when in locked position.

6. A removable container lid having a tube therethrough with compressible material between the tube and the lid, and a locking means comprising a strap member mounted on the tube and engageable with the compressible material, and on said strap member oppositely disposed jaws, each of said jaws having a width not less than ten degrees of the arc of the circumference of the lid.

7. A lid having a tube therethrough with compressible material between said tube and said lid and engaging said compressible material, a locking means comprising a strap member riding said tube and engaging the compressible material, said locking means comprising a fixed jaw at one end of the strap member having a width of not less than ten degrees of the arc of the circumference of the lid, and an adjustable jaw at the other end of said strap member comprising a lever riding in a slot in the end of said strap member and carrying a locking jaw having a sharpened edge.

8. A container lid having a tube therethrough, compressible material between the tube and the lid, and flexible compressing means for tightening said material against the tube and the lid, said flexible compressing means comprising a metallic strap having a fixed hook at one end and a slot in the other end in which rides an adjustable lever having a jaw member.

9. The container lid set forth in claim 8 wherein the adjustable lever comprises an S-shaped member having a sharpened arcuate biting edge for engaging the outer under edge of a container and a wing member at the other end for manual operation.

CARL F. NOTH.
